SOLDERING TOOL OR SIMILAR ARTICLE

Charles D. Baxendell, Downingtown, Pa., assignor to
Westinghouse Electric Corporation, a corporation
of Pennsylvania

Filed Jan. 28, 1966, Ser. No. 816

Term of patent 14 years

(Cl. D26—1)

FIGS. 1-5, inclusive, are top, side, bottom, front, and rear views, respectively, of my invention.

The side not shown in FIG. 2 is substantially similar to the side shown therein.

The dominant features of my design reside in the portions shown in full lines.

I claim:

The ornamental design for a soldering tool or similar article, substantially as shown and described.
